UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,373,482.

Specification of Letters Patent.

Patented Apr. 5, 1921.

Application filed April 11, 1917. Serial No. 161,341.

To all whom it may concern:

Be it known that I, MATTHIAS BROCK, a citizen of the United States, residing at Boston, in the county of Suffolk and State 5 of Massachusetts, have invented certain Improvements in Lasting-Machines, of which the following description, in connection with the accompanying drawings, is a specification, like reference characters on the 10 drawings indicating like parts in the several figures.

This invention relates to lasting machines and particularly to machines of the type employed for end lasting. An object of the 15 invention is to improve machines of this type, including those made in accordance with my prior patents, in respect to the organization and construction of certain mechanisms for the purpose of securing a better 20 conforming operation, reducing labor of manipulation and securing economies in cost and maintenance of the machine.

One feature of the invention consists in a 25 novel construction affording provision for quick and accurate adjustment of toe embracing wipers laterally of a shoe into the correct angular relation to the shoe, the construction shown comprising means for adjustably predetermining different positions 30 of the wipers for the right and left shoes of a pair and for retaining the wipers in adjusted position. With this feature, in the construction shown, is further provided an eccentric lock to clamp the parts rigidly in 35 angularly adjusted relation. These improvements enable precision of toe wiping to be effected relatively to the sewing rib of welt shoe insoles.

Another important feature of the invention 40 having an improved product for its object is the provision of means arranged to occupy over the feather of an insole a position in which it presents an end face in substantial continuation of the end face of the 45 last for coöperation with upwiping wipers in maintaining frictional engagement between the wipers and the wiped up upper until the wipers have reached an elevation at which they can be closed over the feather. 50 In the machine illustrated this means comprises a member which serves additionally as a hold down for the marginal edge of the sole or insole, and a further feature of the invention is to be recognized in a novel con-

struction and arrangement of sole edge 55 hold down means.

A feature of the invention saving labor of the operative consists in novel means for relieving the pressure of the lasting mechanism on the shoe, the construction shown 60 comprising novel controlling means arranged to permit the toe rest to descend for relieving the downward pressure of the wipers on the overwiped stock momentarily to allow the operative to pull a binding wire between 65 the wipers and the shoe into binding relation to the overwiped upper. Formerly the operative had to raise the wipers and the toe lasting head for this purpose.

A further feature of the invention 70 consists in an improved construction of multi-part wipers, including means for bracing the end members to secure rigidity and durability and means for obtaining ready and secure adjustments.

Among its other features the invention 75 comprises a novel construction of toe rest designed to facilitate adjustments in conformity to the shape and position of the shoe, means for timing in a novel manner 80 movements of the toe rest relatively to other mechanism coöperating therewith in the jacking of the shoe, a novel construction of hold down mechanism including means designed particularly to facilitate movement 85 of the hold down into and out of operative position without objectionable interference with parts of the work, novel means of manual control for the lasting mechanism constructed for ready adjustment to suit the 90 convenience of different operators, and a novel construction of supporting means for the heel end of the last.

These and other features of this invention, including certain combinations of 95 parts and more important details of construction, will appear more fully from the following description in connection with the annexed drawings and will then be particularly pointed out in the claims.

Figure 1 of the drawings is a side elevation of an illustrative embodiment of this invention in a toe and heel lasting machine of the type shown in United States Letters Patent No. 1,018,477, granted on my application on Feb. 27, 1912.

Fig. 2 is a vertical transverse section on line 2—2, Fig. 1, looking toward the left.

Fig. 3 is a vertical longitudinal section through portions of the machine on the median line thereof.

Fig. 4 is a plan view of the rear and 5 middle portions of the machine illustrating particularly the heel lasting mechanism.

Fig. 4^a is a plan view of the wipers shown in Fig. 4 with the covering plate removed to disclose the construction of the wiper members. 10

Fig. 5 is an enlarged longitudinal vertical section through the hold-down and the fore-part of a shoe.

Fig. 6 is a perspective view of the parts 15 shown in Fig. 5.

Fig. 7 is a transverse vertical section, with parts in elevation, showing the new heel support construction.

Fig. 8 is a section on line 8—8, Fig. 4.

20 Fig. 9 is a perspective view of the toe head swinging adjustment.

The machine comprises a base or frame adapted to stand on the factory floor and to carry toe and heel lasting mechanisms between which shoe supporting means is located. The frame carries a counter shaft near the floor, Fig. 1, on which is a loose pulley 2 connected by a one-revolution clutch, not seen, to a crank from which an operating rod 4 extends to the front side of a cam shaft 5, Figs. 2 and 3. The rod operates a circularly movable pawl carrier, Fig. 2, having a pivotally mounted pawl 6 engaging a six-tooth ratchet disk fast on the cam shaft. The organization is such that one revolution of the counter shaft turns the cam shaft one-sixth of a revolution. The first treadling of the machine causes the power to advance the cam shaft 5 one-sixth 30 of a revolution and to effect those operations that are concerned with the jacking of the shoe, after which the machine comes to rest for hand manipulations customary in the lasting operation as practised with this 40 type of machine. The second treadling of the machine causes the power to turn the cam shaft another step, during which the shoe is released and the parts positioned to receive another shoe. As the cam shaft is 50 turned only one-third of a revolution for the lasting of each shoe, each of the cams is made with the same formations on each of the thirds of its surface, as may be seen, for example, in the toe rest lifting cam 10 shown 55 in Fig. 2.

The toe rest is supported by a slide 12 movable up and down in guides in the machine frame. The cam 10 acts for the purpose of such movement against a lever 13, 60 pivoted at one end to said slide 12 and movably connected to the slide at its other end by toggle links 15, 16, the arrangement and special function of which will be subsequently explained. The slide 12 is of small 65 thickness longitudinally of the machine,

while the toe rest is required to have a long range of adjusting movement lengthwise of the machine for different sizes of shoes because in this machine the heel post, which co-operates with the toe rest in supporting the shoe, occupies an approximately constant position for all lengths of shoes. The slide 12 is therefore provided with a toe rest supporting member 18, see Figs. 2 and 3, that extends forwardly and backwardly 75 therefrom and is adjustably held rigidly in the slide. For effecting vertical adjustment of the member 18 it is provided with a stem extending through bearings in the slide 12 and threaded to receive, between two bearings, a nut the periphery of which is toothed to be rotated by a pinion on the shaft of a hand wheel 19, located above the slide 12 where it is conveniently accessible to the operator. 80

The toe rest, Figs. 2 and 3, has a stem 20 freely slidable vertically through a guide sleeve on a bar 22 that is itself slidable horizontally on the under side of the toe lasting head plate 24 and pulled forwardly by a spring, Fig. 3, being controlled by an adjusting screw 25. The toe rest stem can turn freely to a limited extent (determined by a wide keyway and a narrow key, Fig. 2) 90 about a vertical axis to adapt the rest, see Fig. 4, to the shape of the top faces of right and left lasts. Centering springs 26 extend from a stud on the left side of the stem 20 to brackets 27 on the front and rear sides of the toe lasting head plate 24. The head of the toe rest stem 20 is channeled transversely 95 of the machine to provide a guideway in which the base piece or holder 28 of the rest is movable to adjust the shoe engaging portion of the rest in a right line transversely 100 of the machine, and of the shoe therein, to adapt it for sustaining in practically identical manner right and left crooked lasts. The holder or base piece is locked in transversely adjusted position by a semi-circular 105 flange 291 (Fig. 2) on a locking rod 29, Fig. 2, journaled in the head and having a bent-down handle which, by gravity, keeps the flange normally in engagement with one or another of three slots in the base piece. The base piece has in its top face a semi-circular 110 recess in which the toe rest cup 30 can slide in an arc extending transversely of the machine. The base piece carries a spring locking pin 32 adapted to engage one or another 115 of three notches to hold the rest cup tilted to one side or the other or central, the latter position being shown in the drawings. The cup 30 carries the rest cushion which may advantageously be a proper composition of rubber into which the shoe can be 120 embedded to some extent by pressure exerted by the hold-down, to be described, to hold the tip seam from displacement during the toe lasting operation. As above indicated 125 130

cated, the toe rest is connected with the toe lasting head which latter is adjustable longitudinally of the machine by hand wheel 35 as usual and as appears more in detail in 5 said prior patent.

The toe lasting head plate 24, previously mentioned, is made in two superposed parts dove-tailed together as heretofore proposed by me for relative adjustment in a right line 10 transversely of the machine between the toe post, which is associated with the lower part, and the toe wipers which are associated with the upper part. In the construction shown, the wiper carrying yoke 31, Fig. 9, is also 15 mounted for curvilinear adjustment transversely of the machine. The yoke has a depending button 33, Figs. 1 and 9, seated in the upper part of plate 24, which latter has also a dove-tailed arc-shaped groove 37 into 20 which a depending flange on yoke 31 fits. A transverse slideway 39 is also cut in the upper part of the plate 24 in which blocks 41 are adjustable by a right and left screw 43. These blocks contain spring pins adapt- 25 ed to seat in recesses in the lower side of a tail piece 47 on the yoke so that as the yoke is adjusted angularly it can be stopped in accurate position for the right and then the left shoe of the same style without special 30 attention from the operator. Accurate toe lasting of welt shoes against the rib of the insole requires precision in the angular position of the wiper carrying parts and to eliminate lost motion and secure this accuracy 35 an eccentric lock 49 is mounted in plate 24 to clamp yoke 31 rigidly in adjusted position.

The heel post 50, which is the coöperating member of the shoe supporting means, is 40 carried by the heel lasting head which latter is pivoted at 36, see Fig. 3, to the frame of the machine for angular adjustment transversely of the machine, as also more fully explained in said prior patent. The heel 45 lasting head, however, has no commonly used adjustment longitudinally of the machine but remains in fixed longitudinal position for shoes differing in length, within certain limits. There is provided, however, 50 as shown in Fig. 3, a setting-up adjustment by which the pivot bolt 36 and the heel lasting head can be moved forwardly and backwardly to adapt the same construction of the machine for use on children's and on 55 women's and men's shoes. The heel post is slideable vertically through a guide sleeve on a slide 38 that is movable lengthwise of the machine in the heel lasting head against the tension of a spring 74 by means of a rack 60 and gear, to the latter of which is connected a hand wheel 40, Fig. 1, this mounting for the heel post being similar to the described mounting of the toe rest upon the toe lasting head. The heel post rests downwardly upon 65 a cam plate 42 which is pivoted on the slide

38 and the inclined lower face of which rests upon a yielding support mounted in the heel lasting head in such position that when the heel post slide 38 is retracted the heel post is 70 yieldingly uplifted to position the shoe 75 against the lower edge of the heel seat wipers simultaneously with the retraction of the heel post and last to seat the shoe in the heel band. This movement of the heel post is effected by the hand wheel 40 which for this 75 purpose has a hand lever 45 comprising a hand portion proper extending radially with relation to the periphery of the hand wheel and a broadened portion extending from adjacent to the rim of the hand wheel into 80 position to be clamped at its inner end to the axle of the hand wheel. The handle member is furthermore clamped by two bolts 46 and a cross member to one of the spokes of the hand wheel at a point adjacent to the 85 rim of the wheel. This construction has been adopted to overcome the difficulties which have been experienced with handles attached to the hand wheel by other methods.

The heel post 50 has, as shown in Fig. 7, 90 a reduced stem permitting it to tip laterally of the machine in the slide 38 against the resistance of its centering springs 51. The last pin 52 is pivoted in the upper end of the post so that it can tip in the same plane and 95 is held against loose movement by a toothed friction pin 53 engaging a toothed segment on the last pin. This combination is arranged to permit centralization in the machine of lasts in which the pin hole is bored 100 obliquely, as is sometimes done accidentally, and some times purposely because of the thinness of some women's lasts. The improved heel post and pin combination allows the center of the heel seat of such a last, or 105 the upper end of the last pin 52 within the last, to be located vertically over the lower end of the post 50.

In the use of the machine the shoe is forced backwardly into the heel band and 110 raised to the proper relation to the wipers by manipulation of the hand wheel while the heel band is open, the shoe being free at this time to move backwardly over the toe rest, the hold-down not yet having been 115 applied to the forepart of the shoe.

The heel embracing band is closed by the power mechanism to clamp the shoe firmly in position in the machine, and in so doing, to conform the upper materials to the side 120 faces of the rear part of the last. This result is effected by a cam 60, Fig. 3, mounted on the cam shaft 5, transmitting motion through a lever 62, resembling the lever 13, and two-part rod 64 to a lever 65 yieldingly 125 connected to thrust bar 66 which is operatively connected to the ends of the heel band substantially as shown in said prior patent through mechanism which is well known and is not necessary here to describe. It 130

will be understood that the described power operation of the heel band for clamping the shoe takes place on the first treadling of the machine and is commonly referred to as constituting, with the described manipulation of the hand wheel 40, the jacking of the shoe. It may be pointed out that during the movement of the cam shaft 5, effected by this first treadling of the machine, the toe rest cam 10 is turned through approximately 60° to the position shown in Fig. 2, and it will be observed that, contrary to the organization of lasting machines as heretofore built, this cam is formed to hold the toe rest stationary in its elevated position during the jacking of the shoe. Heretofore the toe rest has been lifted simultaneously with the closing of the heel band and under some conditions this elevation of the toe end of the last while the heel band is in frictional contact with the upper has produced wrinkles in the rear part of the upper. This disadvantage is eliminated by the present construction of the toe rest cam 10 which, as may be seen from Fig. 2, is formed at 70 to permit the descent of the toe rest during the second treadling of the machine (or unjacking of the shoe), the formation of the cam again raising the toe rest before the cam shaft 30 comes to rest, thereby leaving the toe rest in its elevated position at the end of the unjacking operation instead of in its depressed position as in my said prior patent.

The purpose of lowering the toe rest during the unjacking operation is to facilitate the removal of the shoe. It may be briefly explained that for the purpose of facilitating the application and removal of the shoe to and from the heel post, the heel lasting head is movable longitudinally of the machine on a track which constitutes the base of the heel lasting head, rollers 68, Fig. 3, being provided to facilitate this movement and the head being latched in its forward position by a catch 72, Fig. 1. The catch is lifted by the power mechanism as one of the first steps in the unjacking operation and the heel lasting head is then moved rearwardly by reaction of the band closing spring, Fig. 3. This movement of the heel lasting head carries the shoe rearwardly with relation to the toe rest and it is to facilitate the movement of the shoe over the toe rest that the toe rest is lowered at this time. The springs 26 are arranged to produce a prompt downward movement of the toe rest when its cam 10 permits.

After the shoe has been jacked, the fore-part of the shoe must be clamped upon the toe rest to hold the shoe firmly for the lasting operation. This result is obtained by a hold-down which has the further purpose of confining the insole snugly upon the bottom face of the last so that in the toe lasting operation the upper may be tightly

drawn over the shoe bottom. The hold-down mechanism comprises a vertically movable post 75 located back of the machine and operated by a foot treadle 76 with which is associated a locking bar 77 and a pawl 78 connected with a lifting rod 79, Fig. 1, movable by a knee lever 79. From the head of the post extends a hold-down arm 80 that is normally swung into a position extending longitudinally of the last. Prior to depressing the hold-down this arm is manually swung toward the operator so that it extends transversely across the machine, the operator placing the hold-down on the shoe as indicated in Figs. 3, 5 and 6, in proper longitudinal relation to the toe. For the purpose of facilitating the accurate presentation of the hold-down to and its withdrawal from the sole, the hub of the arm 80 is sleeved on the post and provided with a spiral slot 81 taking a stud on the post and arranged to lower and raise the arm automatically as it is swung toward and from operative position. A return spring swings the arm back when allowed to do so. In prior machines the spring impelled backward movement of the arm, occurring immediately upon release of the pressure of the hold-down on the shoe, has sometimes resulted in displacement of lasting tacks by reason of insufficient clearance between the hold-down and the plane of the sole. By the present invention this difficulty is entirely overcome through the provision of means insuring such elevation of the hold-down proportional to its backward movement as to afford ample clearance. The shoe engaging members of the hold-down comprise a shoe clamping member 82, located under the free end of the bar 80, and forwardly extending insole tip holding members. These members comprise a resilient finger 85 having on its lower face a button adapted for detachable engagement with a crescent-shaped plate 86 formed to engage the insole immediately back of the sewing rib thereof and preferably curved to conform approximately to the curvature of the sewing rib around the toe. This member 86 has a vertical wall adapted to back up the sewing rib when the wipers lay the upper over the feather of the insole and form it against the sewing rib, said member and the wipers constituting a mold in which the upper is given definite shape in proper relation to the sewing rib.

In addition to the above described parts, the insole engaging devices of the hold-down, in accordance with this invention, comprise a plate 90 guided on the top face of the finger 85 for longitudinal sliding movement, said plate 90 being formed at its front end to extend downwardly in front of the rib supporting member 86 and in front of the insole rib and to engage the

feather of the insole at the extreme front edge of the feather. The plate 90 is normally held in feather engaging position by a spring 88 seated between the arm 80 and 5 the rear end of plate 90. Said plate 90 is further formed with a downwardly and forwardly inclined face 92, constituting a wedge moved by the spring 88 under the head of a stud 94, the coöperation of said 10 wedge, stud and spring effecting downward pressure of the plate 90 against the feather of the insole. The normal working position of the parts of the hold-down are shown in Figs. 5 and 6 from which it may be seen 15 that the front face of plate 90 constitutes a wall in substantial continuation of the front end face of the last.

In the usual operation of the machine the wipers are engaged with the upper in the 20 dotted line position shown in Fig. 5 and then are raised to wipe the upper upwardly about the toe of the last until they reach an elevation at which they can be closed to gather the upper inwardly over the feather of the 25 insole. A difficulty has been experienced in getting tight toe lasting because the wipers lose to some extent their frictional hold upon the upper just before they arrive at an elevation which will permit them to be closed 30 over the feather of the insole. The end face of the plate 90 constitutes means coöperating with the wipers to insure a continuation of the frictional hold of the wipers upon the stock until they have reached an elevation 35 permitting them to be closed. The yielding mounting of the plate 90 by its spring 88 permits the plate to be forced backwardly by the wipers when they are closed. The head of the plate 90 has on its lower side an 40 inclined face resting upon the rib supporting member 86 and guiding the head of the plate 90 upwardly as it is forced backwardly. In addition to the assistance afforded by the plate 90 to the wipers in drawing the upper 45 snugly over the toe of the last, said plate holds the extreme edge of the feather snugly down upon the last bottom so that the upper can be tightly drawn over the edge of the feather, and there is no danger of wrinkling 50 or rolling backwardly the edge of the feather.

The upwardly wiping movement of the wipers above referred to for conforming the upper to the side faces of the toe part of the 55 last is effected by an elevation of the entire toe lasting head which, for this purpose, is mounted on a plunger 100, Fig. 1, guided for sliding movement in the left hand end of the machine frame and partially counterbalanced by springs 102. The plunger is connected by a vertical rod with a crank on the shaft 104 which is arranged to be manually operated by a novel mechanism. It may be explained that, in addition to the 60 upward wiping motion of the wipers, they

are required to apply, after they have been closed over the feather of the insole, a downward pressure for ironing down and compacting the overwiped materials. For the purpose of imparting these movements to 70 the wipers and the heavy wiper carrying head, the rock-shaft 104 has rigidly secured to it a block 105, and pivotally secured to the rock-shaft is an arm 106 having a depending lug in which is mounted an adjustable stop screw 108 in position to engage a depending portion of the block 105 and, in response to foot pressure on the arm 106, to turn the rock-shaft in the direction to lift the plunger 100 and the toe lasting head and 80 wipers. By adjustment of the stop screw 108 the position of the arm 106 can be suited to the convenience of the operator and to the length of stroke required to lift the wipers, 85 shoes which are designed to have a high heel requiring the toe to be supported higher, see Fig. 1, than those which are to be made with a low heel, such as the shoe indicated in my said prior patent. A second arm 110 adapted to receive foot pressure is pivotally 90 connected to the right hand end of the block 105 which is extended to give a long leverage to arm 110 for applying powerful ironing-down pressure. The arm carries a stop screw 112 in position to engage a face on 95 the block 105 whereby pressure applied to the arm 110 will turn the block 105 and the rock-shaft in the direction to force down the toe lasting head and the wipers for applying the ironing-down pressure to the shoe. The 100 position of the arm 110 can be adjusted by means of the stop screw 112 to suit the convenience of the operator. These adjustments are important because the lifting and depressing of the toe lasting head is one of the 105 laborious portions of the work of a lasting machine operator and this provision for rendering a portion of his work easier reduces his fatigue. The energy thus saved is available for application in greater attentiveness 110 to his work or in lasting a larger number of shoes during his working hours.

The toe embracing wipers which are indicated at 115 are advanced and closed to embrace the toe of the shoe preparatory to the 115 wiping movement and are subsequently further advanced and closed to gather the upper materials over the feather of the insole by movement transmitted to them from a hand lever 116 and suitable connections 120 which are or may be similar to those described in said prior patent. After the wipers have been manipulated to work the upper into satisfactorily lasted position around the toe of the shoe, it is customary 125 in the manufacture of welt shoes to fasten the upper in lasted position by a binder of wire that is usually anchored first at the rear side of the shoe and then drawn snugly around the toe and anchored to a tack on the 130

front side of the shoe. After the free end of the binder strand has been anchored and before it can be drawn into holding relation to the upper around the toe it is necessary to relieve the pressure of the wipers upon the overlasted upper materials in order to draw the binder into position under the wipers. It has heretofore been customary to require the operator, by means of the treadle mechanism above described, to raise the entire toe lasting head in order to lift the wipers enough to get the wire in place. In accordance with the present invention the labor required for this operation is greatly reduced. As earlier explained, the toe rest is supported by a slide 12 that is moved by the power cam 10, Fig. 2, through connections including the toggle members 15, 16, the latter of which is pivoted to the slide at 120. The toggle is normally straight as shown in Fig. 2 but can be flexed or broken to shorten the distance between the pivot point 120 and the supporting lever 13, Fig. 2. This flexing of the toggle can be accomplished by force transmitted through rod 122 from a foot treadle 124, depression of the treadle serving to rock link 16 about pivot 120. The flexing of the toggle thus produced allows the toe rest to drop, thereby momentarily relieving the upward pressure of the shoe against the wipers sufficiently to permit the operator to draw the wire in between the wipers and the overlasted upper lying upon the feather of the insole. It will be noted that this system for permitting the wire to be drawn into place has a substantial advantage over the prior practice of lifting the wipers by means of the treadle arm 106 because in the new system the pressure of the wipers is not entirely removed from the upper but is only relieved momentarily, the weight of the heavy toe lasting head pulling the wipers down to the new level of the shoe. In a very satisfactory use which has been made of the system, the operator times himself to pull the wire in concurrently with the flexing of the toggle and no slackening back of the upper occurs before the wipers again come into satisfactory holding relation to the upper outside of the binder. The treadle 124 has an extension 125 located on the forward side of its pivot and arranged to permit the operator to apply force for manually straightening the toggle 15, 16 to return the toe post to elevated position. It is ordinarily not necessary to do this, however, because under most conditions the toe post may remain in its lowered position until the shoe is unjacked and means is herein provided by which to straighten the toggle automatically during the unjacking operation. This means comprises a downward extension of toggle link 16 into the path of a stud 128 carried by a disk on the cam shaft and operating to turn

the link 16 into toggle straightened position as the stud travels past the lower end of the link.

It has been stated that the heel lasting mechanism is carried on a lasting head that is adjustable transversely of the machine about an axis 36. This affords adjustment of the heel post, heel band and heel wipers together for right and left crooked lasts. In modern lasts, the heel ends of which are themselves unsymmetrical, as may be understood from the plan view of a shoe on such a last in Fig. 4, there is need for additional lateral adjustment of the heel wipers relatively to the heel band, and I have shown in Fig. 4 the best construction of wipers and arrangement for their adjustment which I have yet devised.

The heel lasting head, which carries the heel band 130 and its operating mechanism referred to in connection with the jacking operation, also is provided with a circular track in which a wiper carrying plate 136 is confined by gibs 138. The plate 136 has a rigid arm 140 projecting rearwardly over the wiper operating plunger 134, which is movable by hand lever 135 as usual to open and close the heel wipers. In the rear end of arm 140 is a short rock-shaft 141 on the lower end of which is fastened a longitudinally slotted plate 142, see Fig. 3 as well as Fig. 4, and on the upper end of the rock-shaft is rigidly attached an adjusting member 144 carrying a locking pin 145 adapted to be entered into any one of a row of holes located in an arc in the arm 140. The slot of plate 142 is occupied by a roll 148 carried on a slide 150 that is guided for movement by and parallel with the wiper operating plunger 134. It will now be understood that when the slotted plate 142 is adjusted out of parallelism with arm 140, the slot constitutes a cam track by means of which the roll on the slide 150 turns the wiper carrying plate toward the right or the left simultaneously with the operation of the wipers for gathering the upper over the heel seat of the shoe. The resulting movement of the wipers is farther inwardly from starting position at one side of the heel seat than at the other side. Features of this construction have been claimed in a copending application upon which were granted Letters Patent No. 1,284,870 on Nov. 12, 1918.

The embracing wipers that are operated by hand lever 135 and plunger 134 are connected to the latter by cross-bar 152 and links 154 which, of course, travel with the wiper carrying plate 136, there being a pin and slot connection at 153. The links 154 diverge forwardly with relation to one another and are pivotally connected to wiper cam plates 158 having arc-shaped outer edges bearing against adjustable wedge-shaped steel plates 156, and guided by roll 130

studs standing in slots 159. To the lower face of the cam plates 158 are bolted hinged rear end wipers 160 which gather the upper over the rear end and corners of the heel as shown in Fig. 4, by an inward closing and forward advancing movement derived from the cam plates. On the lower side of the wipers 160 are mounted side wipers 162 for longitudinal sliding adjustment relatively to the end wipers 160. The mounting is such that the wipers 162 are carried inwardly by the wipers 160 but do not partake of the forward movement of wipers 160, being held longitudinally stationary by links 164 pivoted to wipers 162 at 163 and having rolls engaging longitudinally extending slots in plates 158, said links at their rear ends being adjustably pivoted to the carrying plate 136 at 165 by studs having wing nuts which can be easily loosened to permit the side wipers to be adjusted forwardly or backwardly for long or short heel seats. Each side wiper 162 supports a front wiper 170 pivotally connected to it at 172 and adjustable in or out about said pivot by a thumb-screw 175 connecting arms 173 and 174 extending respectively outwardly and forwardly from said wipers into position for the thumb-screw to be conveniently manipulated in adjusting the front wiper to extend more or less inwardly. It is frequently required to adjust so that the front wiper reaches farther inwardly at the inner side of the shank than at the outer side. In the illustrated construction the front wipers have only movements derived from and common to the side wipers 162 and they are braced against upward displacement by flanges 176 extending from the side wipers over the front wipers.

Having described the invention, what I claim as new and desire to secure by Letters Patent of the United States is:—

1. In a lasting machine, the combination with toe lasting mechanism, of means for supporting a shoe comprising a toe rest having a shoe engaging member extending transversely across the shoe, mountings therefor permitting said member freely to turn about a vertical axis to adapt itself to an inclination rearwardly toward the right or toward the left of the top face of a right or a left crooked last respectively, and means to hold the rest normally in centralized position.

2. In a lasting machine, the combination with toe lasting mechanism, of means for supporting a shoe comprising a toe rest having a shoe engaging member extending transversely across the shoe, a toe rest stem having a head channeled transversely of the machine, a toe rest base piece adjustable in said channel transversely of the machine, and locking means journaled in the head and having a locking member to coöperate with

one or another of locking formations on the base piece to hold the latter positioned for sustaining in practically identical manner right or left crooked lasts.

3. In a lasting machine, the combination with toe lasting mechanism, of means for supporting a shoe comprising a toe rest having a shoe engaging member extending transversely across the shoe and having a convex bearing face that can slide in an arc extending transversely of the machine, a holder having a concave recess in which the shoe engaging member is mounted, and means to lock said shoe engaging member in transversely adjusted position in the holder with its shoe engaging face inclined toward one side or the other of the machine.

4. In a lasting machine, the combination with toe lasting mechanism, of means for supporting a shoe comprising a toe rest having a shoe engaging member extending transversely across the shoe, said toe rest being mounted for free right line adjustment transversely of the machine and for angular movement on a vertical axis to adapt it for supporting in similar manner shoes on right and left crooked lasts.

5. In a lasting machine, the combination with toe lasting mechanism, of means for supporting a shoe comprising a toe rest having a shoe engaging member extending transversely across the shoe, said toe rest being mounted for adjustment transversely of the machine about a horizontal axis and for free angular movement on a vertical axis to adapt it for supporting in similar manner shoes on right and left crooked lasts.

6. In a lasting machine, the combination with toe embracing wipers and a toe rest, of mountings for the wipers constructed and arranged to permit angular adjustment of the wipers transversely of the machine and relatively to the toe rest, and means automatically operative to limit such adjusting movement of the wipers and adjustable to vary said limit of movement.

7. In a lasting machine, the combination with toe embracing wipers and a toe rest, of mountings for the wipers constructed and arranged to permit angular adjustment of the wipers transversely of the machine and relatively to the toe rest, and means adjustable to a predetermined position to limit the subsequent adjusting movement of said wipers, said means being constructed to hold the wipers in the angular position predetermined by its adjustment.

8. In a lasting machine, the combination with toe embracing wipers and a toe rest, of mountings for the wipers constructed and arranged to permit angular adjustment of the wipers in opposite directions transversely of the machine and relatively to the toe rest to adapt the wipers to right and

left toes, and complementary wiper-positioning means adjustable to predetermined positions to limit the subsequent adjusting movements of said wipers, said means being constructed to hold the wipers in the reverse angular positions for right and left toes of a pair predetermined by its adjustment.

9. In a lasting machine, the combination with toe embracing wipers and a toe rest, 10 of mountings for the wipers permitting angular adjustment of the wipers transversely of the machine relatively to the toe rest, and an eccentric friction lock to clamp the parts rigidly with the wipers in adjusted position.

10. In a lasting machine, the combination with a toe rest, a heel post and a heel embracing band, of means for operating the heel post to seat the last in the heel band, 20 and power operating mechanism with which the toe rest and the heel band are connected for jacking and unjacking the shoe, said mechanism being organized to maintain the toe rest in elevated position during the jacking operation and to lower the toe rest and 25 then return it to elevated position during the unjacking operation.

11. In a lasting machine, the combination with a toe rest and lasting mechanism with 30 relation to which the rest supports the toe of the shoe, of a holddown arranged to be moved from beyond the supported shoe to a position over and against the shoe sole to clamp the shoe on said toe rest, and means 35 for imparting return movement to said holddown constructed and arranged to insure such a component of movement in a direction transverse to the plane of the sole as to cause it to clear the lasting tacks at the edge 40 of the sole.

12. In a lasting machine, the combination with a toe rest and lasting mechanism with relation to which the rest supports the toe of the shoe, of a holddown arranged to be 45 moved from a position beyond the supported shoe to a position over and against the shoe sole to clamp the shoe on said toe rest, and guiding means constructed and arranged to insure such movement of the holddown in a 50 direction transverse to the plane of the sole in its return to starting position as to avoid contact of the holddown with the lasting tacks at the edge of the sole.

13. In a lasting machine, the combination 55 with a toe rest and lasting mechanism with relation to which the rest supports the toe of the shoe, of a holddown supported for movement from a position above and to one side of a supported shoe laterally over and 60 down into engagement with the shoe sole to clamp the shoe on the toe rest, and means for moving the holddown away from the sole constructed and arranged to impart to it an upward movement in such relation to 65 its reverse lateral movement as to insure

clearance between the holddown and the lasting tacks at the edge of the sole.

14. In a lasting machine, the combination with a toe rest and lasting mechanism with relation to which the rest supports the toe 70 of the shoe, of a holddown having a supporting arm mounted to move the holddown laterally from a position at one side of the shoe over the shoe and down upon the shoe sole to clamp the shoe on the toe rest, and means automatically to move the holddown away from the sole including mechanism co-operating with said arm automatically to lift the arm and raise the holddown above the plane of the sole in consequence of its 80 movement laterally away from the shoe.

15. In a lasting machine, the combination with a toe rest and lasting mechanism with relation to which the rest supports the toe of a shoe, of a holddown having a supporting 85 arm mounted to move the holddown from a position above and at one side of the shoe over and down upon the toe end of the shoe sole to clamp the toe of the shoe on the toe rest, and means for automatically moving the holddown upwardly and outwardly 90 from the toe end of the sole including guiding means co-operating with said arm automatically to lift the holddown above the plane of the sole as it is moved outwardly 95 from over the sole.

16. In a lasting machine, the combination with a toe rest and lasting mechanism with relation to which the rest supports the toe of a shoe, of a holddown movable to engage 100 the toe end of a shoe sole to clamp the toe of the shoe upon the toe rest, and means supporting said holddown for swinging movement laterally of and away from the shoe including guide mechanism constructed to 105 impart to it simultaneously movement in a direction transverse to the plane of the shoe sole.

17. In a lasting machine, the combination with a toe rest and lasting mechanism with 110 relation to which the rest supports the toe of the shoe, of a hold-down comprising an arm mounted to swing about a vertical support located back of the lasting mechanism and constrained to have a component of vertical movement dependent upon said swinging movement.

18. In a lasting machine, the combination with a toe rest and lasting mechanism with relation to which the rest supports the toe 120 of the shoe, of a vertically movable hold-down post located at the rear side of the machine, a treadle for depressing the post, a horizontal supporting arm sleeved on the post, a hold-down foot on the arm, and a 125 spiral pin and slot connection between the post and arm arranged to impart a vertical component of movement to the arm as it is swung toward and from operative position over the toe.

19. In a lasting machine, the combination with means for supporting a shoe and means comprising toe embracing wipers constructed and arranged to wipe the upper upwardly about the toe of the last while leaving the unwiped margin of the upper freely upstanding from the plane of the wipers and then to wipe the upper inwardly over the feather of the insole, of means arranged to 5 occupy a position over the feather of the insole in which it presents an end face in substantial continuation of the end face of the last for coöperation with the wipers in maintaining frictional engagement between 10 the wipers and the wiped up upper until the wipers have reached an elevation at which they can be closed over the feather.

20. In a lasting machine, the combination with means for supporting a shoe and toe 20 embracing wipers movable to wipe the upper upwardly about the toe of the last and inwardly over the feather of the insole, of hold-down mechanism including a feather engaging member and organized to cause 25 said member normally to engage the edge of the feather and to permit movement thereof backwardly over the insole rib in response to the closing pressure of the wipers.

21. In a lasting machine, the combination with means for supporting a shoe and toe embracing wipers movable to wipe the upper upwardly about the toe of the last and inwardly over the feather of the insole, of 30 hold-down mechanism including a feather engaging member and organized to cause said member normally to engage the edge of the feather and to permit movement thereof backwardly in response to the closing 35 pressure of the wipers, and means for guiding said member upwardly over the insole rib as it is forced backwardly.

22. In a lasting machine, the combination with means for supporting a shoe and toe 45 embracing wipers movable to wipe the upper upwardly about the toe of the last and inwardly over the feather of the insole, of hold-down mechanism comprising a rib supporting member and a feather holding 50 member yieldingly mounted and guided by the rib supporting member upwardly and backwardly as the wipers close over the feather.

23. In a lasting machine, the combination 55 with means for supporting a shoe and toe embracing wipers movable to wipe the upper upwardly about the toe of the last and inwardly over the feather of the insole, of hold-down mechanism comprising a resilient 60 finger, a rib supporting member carried by the finger and adapted to engage the insole immediately back of the sewing rib, a feather holding member mounted for longitudinal movement on said finger, a spring 65 maintaining the feather holding member

normally in advanced position, and means coöoperating with the spring for effecting downward pressure of the feather engaging member on the work.

24. In a lasting machine, the combination 70 with means for supporting a shoe and toe embracing wipers movable to wipe the upper upwardly about the toe of the last and inwardly over the feather of the insole, of hold-down mechanism comprising a finger 75 having operative engagement with the insole back of the sewing rib, a feather holder mounted for movement longitudinally of the finger, a spring arranged to maintain the feather holder in advanced position, and 80 wedging means carried by the finger and the feather holder arranged to effect, in response to the force of the spring, downward pressure of the feather holder upon the work.

25. In a lasting machine, the combination 85 with means for supporting a shoe, of toe lasting mechanism having end embracing wipers and movable upwardly to wipe the upper about the toe of the last, a crank shaft and connections therefrom for effecting upward movement of the toe lasting mechanism, a block rigidly attached to the shaft, an arm pivotally attached to the shaft, and adjusting means between the arm and the 90 block by which to position the arm in convenient relation to the floor for the operator to depress the arm and elevate the toe lasting mechanism with his foot.

26. In a lasting machine, the combination with means for supporting a shoe, of toe 100 lasting mechanism having end embracing wipers and movable upwardly to wipe the upper about the toe of the last and movable downwardly to iron down the overwiped materials upon the last bottom, a crank shaft 105 and connections therefrom to the toe lasting mechanism, a block rigidly attached to the shaft, an arm pivotally connected to the block, and adjusting means for positioning the arm relatively to said pivotal connection 110 and in relation to the floor for the operator conveniently to depress the arm for turning the crank shaft in a direction to apply ironing down pressure.

27. In a lasting machine, the combination 115 with means for supporting a shoe, of toe lasting mechanism having end embracing wipers and movable up and down, a crank shaft and connections therefrom to the lasting mechanism for transmitting such movement, and arms extending in opposite directions from the crank shaft and adjustable relatively to one another and to the floor for locating the arms in position for the operator conveniently to apply pressure to one 120 arm and then to the other for effecting the required movements of the lasting mechanism.

28. In a lasting machine, the combination 125 with means for supporting a shoe including 130

a toe rest and means for lasting the shoe including wipers movable to gather the upper over the toe of the last and iron it down, of means adapted to be tripped by the operator 5 independently of the operation of the lasting means to allow the toe rest to descend for relieving the ironing down pressure momentarily to allow the operator to pull a binding wire between the wipers and the 10 shoe into binding relation to the overlasted upper.

29. In a lasting machine, the combination with means for supporting a last including a toe rest, of lasting mechanism including toe 15 embracing wipers which are adapted for movement to gather the upper over the toe of the last, said mechanism being movable upwardly to cause the wipers to form the upper to the side faces of the last and downwardly to iron down the overwiped upper, and means movable by the operator to effect 20 momentarily relief of the shoe supporting pressure to facilitate the drawing of a toe binding wire between the wipers and the 25 overwiped portion of the upper, the lasting mechanism being movable downwardly by gravity to restore the pressure of the wipers upon the shoe in its lowered position.

30. In a lasting machine, the combination with means for supporting a shoe including a toe rest and means for lasting the shoe including wipers movable to gather the upper over the toe of the last and iron it down, of means including a toggle for sustaining the 35 toe rest in shoe supporting position, and means arranged to be moved by the operator independently of the operation of the wipers to flex the toggle.

31. In a lasting machine, the combination with means for supporting a shoe including a toe rest and means for lasting the shoe including wipers movable to gather the upper over the toe of the last and iron it down, of means including a toggle for sustaining the 45 toe rest in shoe supporting position, means arranged to be moved by the operator to flex the toggle and permit the toe rest to move downwardly, and means for restoring automatically the toggle to straightened position.

32. In a lasting machine, the combination with means for supporting a shoe, of end embracing wipers, the wiper on each side of the shoe end comprising a forwardly and 55 inwardly movable corner member, a side member limited to inward movement only and adjustable endwise in the corner member, and a front member pivoted to the side member for adjustment relatively thereto.

60 33. In a lasting machine, the combination with means for supporting a shoe, of end embracing wipers comprising members extending along the sides of the heel end, extension members adjustably mounted thereon to extend farther forwardly along the

sides, and a flange on each side member overlying the extension member and bracing it against upward displacement.

34. In a lasting machine, the combination with means for supporting a shoe, of end 70 embracing wipers comprising members extending along the sides of the heel end, extension members pivotally connected thereto, and a thumb-screw connecting said members to effect adjustment of the extension members about their pivotal connections to the side members.

35. In an end wiper mechanism, a wiper 80 extending along the side of a shoe end, an extension member pivoted to the side member, arms extending from said two members, and an adjusting screw connecting the arms.

36. In an end lasting mechanism, the combination with heel embracing wipers, of shoe 85 supporting means including a heel post the lower end of which is located centrally in lateral relation to the wipers, said post being mounted to tip laterally in a determinate plane, and a last pin mounted on the heel 90 post to tip thereon and constrained to tip in the same lateral plane.

37. In an end lasting mechanism, the combination with heel embracing wipers, of 95 means affording support for the heel end of the last and mounted to tip in a determinate plane transversely of the last at two points in its length such that lasts having laterally inclined pin holes can be supported in centralized relation to the wipers.

38. In a lasting machine, a support for the heel end of a last, heel lasting mechanism in co-operative relation to which said support positions a last and its shoe and which mechanism includes a heel embracing band, a toe rest for supporting the toe of a shoe whose last is mounted on said heel support, and operating mechanism effective relatively to move said band and a supported last and shoe into and out of 100 operative position and including means organized to maintain the toe rest continuously in an elevated position during said relative movement into operative position and to lower the toe rest when the parts are 105 subsequently moved relatively out of operative position.

39. In a lasting machine, a heel post and a heel embracing band arranged for relative movements to position the heel end of a supported shoe and said band in and out of operative relation to each other, a toe rest for supporting the toe of a shoe whose last is mounted on said heel post, and power operated mechanism effective relatively to move 110 the band and heel post to position the heel end of a supported shoe and said band in and out of operative relation to each other, said mechanism being organized to maintain the toe rest in an elevated position during 115 120 125 130

the relative movement of said parts into operative relation to and automatically and in timed relation to lower said toe rest when said parts are moved relatively out of operative relation and subsequently to raise said rest to its initial position.

40. In a machine of the class described, the combination with means for working an upper over a last, of a shoe rest constructed and arranged to engage the top of the forepart of the shoe and mounted to turn toward the right or the left in response to pressure of the shoe about an axis extending in the transverse relation to the plane of the shoe bottom, and yielding means tending to position said shoe rest in a normal intermediate position while permitting it to turn in response to pressure of the shoe.

41. In a machine of the class described, the combination with means for working an upper over a last, of a shoe rest constructed and arranged to engage the top of the forepart of the shoe and adjustably movable laterally of the shoe, said shoe rest being mounted also to turn in response to pressure of the shoe about an axis extending in transverse relation to the plane of the shoe bottom.

42. In a machine of the class described, the combination with shoe positioning means, of a holddown for engaging the sole of the shoe, said holddown being mounted for movement outwardly from over the sole, and controlling means constructed and arranged to act on the holddown in its outward movement to insure substantial clearance between the holddown and the plane of the sole sufficient to avoid interference with the work as it moves outwardly across the edge of the shoe bottom.

43. In a machine of the class described, the combination with shoe positioning means, of a holddown for engaging the sole of the shoe, said holddown being mounted for movement outwardly from over the sole, and means dependent upon said outward movement of the holddown for imparting to it a proportional movement away from the plane of the sole.

44. In a machine of the class described, the combination with shoe positioning means, of a holddown for engaging the sole of the shoe, said holddown being mounted to swing inwardly and outwardly over the sole, and mechanism automatically operative in the respective inward and outward movements of the holddown to cause it to approach and recede from the plane of the sole.

45. In a machine of the class described, the combination with a shoe support, and end embracing wipers constructed and arranged to wipe the upper over the end face of the last by relative movement of said support and wipers and then to wipe the upper in-

wardly over the feather of the insole, of a holddown member arranged to engage the feather of the insole and constructed to present an outer face for supporting the margin of the upper against the pressure of the wipers prior to the overwiping operation, and means supporting said holddown member for sliding movement backwardly over the insole in response to pressure of the wipers as the wipers move inwardly.

46. In a machine of the class described, the combination with a shoe support, and end embracing wipers constructed and arranged to wipe the upper over the end face of the last by relative movement of said support and wipers and then to wipe the upper inwardly over the feather of the insole, of a holddown member arranged to engage the feather of the insole and constructed to present an outer face for supporting the margin of the upper against the pressure of the wipers prior to the overwiping operation, said holddown member being mounted for movement inwardly over the insole in response to pressure of the wipers in the overwiping operation, and means operative in the inward movement of said member to force it away from the plane of the insole and cause it to clear the sewing rib.

47. In a machine of the class described, the combination with a shoe support, and end embracing wipers constructed and arranged to wipe the upper over the end face of the last by relative movement of said support and wipers and then to wipe the upper inwardly over the feather of the insole, of a holddown member arranged to engage the feather of the insole and constructed to present an outer face for supporting the margin of the upper against the pressure of the wipers prior to the overwiping operation, said holddown member being mounted for movement inwardly over the insole in response to pressure of the wipers in the overwiping operation, and means for engaging the insole inside of the sewing rib to support the rib against the closing pressure of the wipers, said rib supporting means being constructed and arranged to cooperate with said holddown member to force said member away from the plane of the insole as it is moved inwardly.

48. In a machine of the class described, the combination with means for working an upper over a last, of a shoe bottom rest for engaging the sole on the last, a sole edge holddown member mounted on said rest for yielding movement inwardly from the edge of the sole in response to pressure of the upper against said member, and wedge mechanism constructed and arranged to force said member away from the plane of the sole as it is moved inwardly.

49. In a machine of the class described, the combination with means for working an up-

per over a last, of a shoe bottom rest for engaging the sole on the last, a member mounted on said rest for engagement with the marginal edge of the sole to position it relatively to the last and for movement inwardly over the sole in response to pressure of the upper against said member, yieldable means against the resistance of which said member is movable inwardly, and means on said rest arranged to coöperate with the holdown member to wedge said member away from the plane of the sole as it is moved inwardly.

50. In a machine of the class described, the combination with toe lasting mechanism, and a toe rest arranged to support the forepart of the shoe while the shoe supports the weight of said lasting mechanism, of means for controlling upward and downward movement of said toe rest including a device arranged to be tripped by the operator to relieve momentarily the pressure of the lasting mechanism on the shoe.

51. In a machine of the class described, the combination with toe lasting mechanism, and a toe rest arranged to support the forepart of the shoe while the shoe supports the weight of said lasting mechanism, of power means for controlling upward and downward movement of said toe rest including a toggle arranged with its arms normally in substantially parallel relation for holding the toe rest in shoe supporting position, and means enabling the operator to break said toggle and thus relieve momentarily the pressure of the lasting mechanism on the shoe.

52. In a machine of the class described, the combination with lasting mechanism, of a member for supporting the shoe against the

pressure of said lasting mechanism, means comprising a toggle arranged with its arms normally in substantially parallel relation for holding said member in operative position, and means enabling the operator to break said toggle to relieve the pressure of the lasting mechanism on the shoe.

53. In a machine of the class described, the combination with a shoe support and end lasting wipers, of power means for controlling the shoe support including a device constructed and arranged to be tripped by the operator independently of the power operation to relieve the pressure of the wipers on the shoe.

54. In a machine of the class described, the combination with end lasting means, of shoe supporting means comprising a member mounted to tip yieldingly in directions laterally of the shoe, a last pin mounted on said member for tipping movement relatively to the member in the same plane, and means for holding said last pin normally against tipping movement relatively to said member.

55. In a machine of the class described, the combination with end lasting means, of shoe supporting means comprising a member mounted to tip in directions laterally of the shoe, spring means tending to hold said member normally in an intermediate position while permitting such tipping movement, a last pin pivotally mounted on said member to tip about an axis extending lengthwise of the shoe, and means for normally holding said last pin against movement about said axis.

In testimony whereof I have signed my name to this specification.

MATTHIAS BROCK.
